UNITED STATES PATENT OFFICE.

ARTHUR C. HOPKINS, OF NILES, MICHIGAN, ASSIGNOR TO NATIONAL-STANDARD COMPANY, OF NILES, MICHIGAN.

LIFTING JACK.

Application filed May 18, 1927. Serial No. 192,266.

The main object of this invention is to provide an improved lifting jack for motor vehicles and the like which is very powerful and at the same time light in weight and compact when collapsed.

Objects pertaining to details and economies of my invention will appear from the description to follow. The invention is defined in the claims.

10 A structure embodying the features of my invention is illustrated in the accompanying drawing, in which:

Fig. 1 is a side view of my improved lifting jack the actuating screw being partially broken away.

Fig. 2 is a detail view mainly in central longitudinal section.

Fig. 3 is a perspective view of a modified form of one of the elements of the lifting 20 member of my improved jack.

Fig. 4 is a detail section of another modification of the lifting member element.

Referring to the drawing, my improved jack comprises a tubular elbow standard 1 comprising an upright portion 2, a horizontal portion 3 and a connecting curved elbow portion 4. These parts are formed integrally and preferably with an integral base 5 at the elbow portion, the upright 30 portion of the standard being disposed centrally of this base for stability.

The lifting member in the embodiment shown in Fig. 2 comprises a coiled spring element 6, the coils being of concavo-convex cross section, and in nesting engagement at the outer end of this element 6 is a head 7 having inwardly projecting shank portion 8 disposed within the end of the element 6. At its other end the element 6 is provided with a thrust member 9, the head and thrust member being connected by the flexible tension member 10 which is in the form of a chain in the embodiment illustrated.

45 This tension member terminates in a threaded rod 11 disposed through the thrust member 9 and provided with a nut 12 so that suitable tension may be applied to clamp the coils together. Thus arranged 50 the projecting portion of the standard is substantially rigid, effectively supporting a load, and at the same time it may be collapsed into the standard, sliding around the bend or elbow as shown in Fig. 2.

55 The tension member should, of course, be

under sufficient tension to engage the coils at the elbow so that there is no substantial variation in the tension on the tension member as the standard is projected or retracted.

60 The actuating screw 13 has threaded engagement with the nut 14 secured on the standard, a bearing block 15 being interposed between the inner end of the screw and the thrust member 9. This block is 65 recessed at 16 to receive the nut 12.

70 In the modification shown in Fig. 3 the standard element corresponding to the element 6 is made up of two coils 17 and 18 threaded together, the coil 17 being formed of cylindrical cross section while the coil 18 has seats 19 therein to receive the coacting coil.

75 In the embodiment shown in Fig. 4 a plurality of annular members 20 are provided having recesses 21 in one side thereof to receive the adjacent coil. The tension members hold these parts in the same relation as the coils in the embodiment shown in Fig. 2.

80 My improved jack is compact in structure, especially adapting it for use in motor vehicles. At the same time it is easy to operate.

I have not attempted to illustrate or describe various modifications or adaptations which I contemplate as I believe this disclosure will enable those skilled in this art to adapt my improvements as may be desired.

90 Having thus described my invention what I claim as new and desire to secure by Letters Patent is:

95 1. In a lifting jack, the combination of a tubular elbowed standard of uniform bore from end to end, the elbow being uniformly curved, said standard having an integral base below its elbow, a lifting member comprising a coiled spring slidably fitting within said standard and having coils of a concavo-convex cross section in nesting engagement, a head for said lifting member mounted on the outer end of said spring, a thrust member engaging the inner end of said spring, a flexible tension member secured to said head and adjustably secured to said thrust member, and an actuating screw having threaded engagement with said standard and coacting with said thrust member.

2. In a lifting jack, the combination of a tubular elbowed standard, said standard having an integral base below its elbow, a lifting member comprising a coiled spring 5 slidably fitting within said standard, a head for said lifting member mounted on the outer end of said spring, a thrust member engaging the inner end of said spring, a flexible tension member secured to said head and adjustably secured to said thrust member, and an actuating screw having threaded engagement with said standard and coacting with said thrust member.
3. In a lifting jack, the combination of a tubular elbowed standard having a bore of uniform diameter from end to end, the elbow being of regular curvature, said standard having a base at its elbow, a lifting member comprising a coil slidably in said standard, a tension member disposed within and connected to the ends of said coil, said lifting member being provided with a head at its outer end, and an actuating means coacting with the inner end of said coil.
4. In a lifting jack, the combination of a tubular elbowed standard, a lifting member comprising a plurality of annular parts disposed in contacting relation and provided with a head at one end and with a thrust member at the other, a tension member connecting said head and thrust member, and an actuating means coacting with the inner end of said lifting member.
5. In a lifting jack, the combination of a tubular elbowed standard, said standard having a base below its elbow, a lifting member comprising a coil element slidable within said standard and having coils conformed for nesting engagement, a flexible tension member disposed within and secured to the ends of said coiled element, a head for said lifting member mounted on the outer end of said coiled element, and an actuating screw having threaded engagement with said standard and coacting with the inner end of said coiled element.
6. In a lifting jack, the combination of a tubular standard, a lifting member comprising a coil slidably in said standard, a tension member disposed within and connected to the ends of said coil, said lifting member being provided with a head at its outer end, and an actuating means coacting with the inner end of said coil.
7. In a lifting jack, the combination of a tubular elbowed standard, a lifting member comprising a plurality of annular parts disposed in contacting relation, a tension member connected to the end parts of the said lifting member, and an actuating means coacting with the inner end of said lifting member.
8. In a lifting jack, the combination of a tubular elbowed standard, a lifting member comprising a plurality of annular parts disposed in contacting relation, a tension member lying within said annular parts and connected to the end parts of the said lifting member, and an actuating means coacting with the inner end of said lifting member.
9. In a lifting jack, the combination of a tubular elbowed standard, a lifting member comprising a plurality of annular parts lying in contacting relation and having coacting concave and convex aligning surfaces, a tension member connected to the end parts of the said lifting member, and an actuating means coacting with the inner end of said lifting member.
10. In a lifting jack, the combination of a tubular elbowed standard, a lifting member comprising a plurality of annular parts disposed in contacting relation and having coacting parts to hold them in alignment, a tension member connected to the end parts of the said lifting member, and an actuating means coacting with the inner end of said lifting member.
11. A lifting member comprising a plurality of parts disposed in alignment in contacting relation and having a line element that elongates when the member is flexed, and a tension member having its ends connected to the end parts of the lifting member and lying in said line element, whereby the elongation of such line element is limited and the flexing of said member correspondingly limited.
12. A flexible lifting member having a line element that elongates when flexing, and a tension member lying in said line element and having its ends connected to the ends of said flexible lifting member, whereby the elongation of such line element is limited and the flexing of said member correspondingly limited.

In witness whereof I have hereunto set my hand.

ARTHUR C. HOPKINS.
